DESIGN FOR A TABLECLOTH OR SIMILAR ARTICLE

George Balish, New York, N. Y.

Application August 12, 1936, Serial No. 64,369

Term of patent 3½ years

To all whom it may concern:

Be it known that I, George Balish, a citizen of the United States of America, residing in city of New York, county of New York, and State of New York, have invented a new, original, and ornamental Design for a Tablecloth or Similar Article, of which the following is a specification, reference being had to the accompanying drawing, forming part thereof.

The figure is a face view of a quarter section of a tablecloth or similar article showing my new design, the other three sections being identical with that here disclosed, arranged in proper relation to complete the tablecloth or similar article.

I claim:

The ornamental design for a tablecloth or similar article substantially as shown and described.

GEORGE BALISH.
